WILLIAM ELMER STUART, OF SAN FRANCISCO, CALIFORNIA.

GAS VALVE FOR HOT-WATER HEATERS.

Application filed July 14, 1919. Serial No. 310,751.

To all whom it may concern:

Be it known that I, WILLIAM E. STUART, citizen of the United States, residing at San Francisco, in the county of San Francisco, State of California, have invented a new and useful Gas Valve for Hot-Water Heaters, of which the following is a specification in such full and clear terms as will enable those skilled in the art to construct and use 10 the same.

This invention relates to a gas valve for hot water heaters an object of which is to immediately fully open or fully close the valve when either operation is to take place. 15 It will be understood by those skilled in the art that upon a gas burner hot water tank reaching a given maximum temperature that it is desirable to immediately close the burner valve completely and similarly 20 upon the tank reaching a given minimum it is necessary to immediately fully open the valve in order to prevent in both instances the gas from flashing back into the burner, the tank ordinarily being maintained at a given temperature within a range 25 of from ten to twenty degrees.

A further object of the invention is to produce a valve with but a single spring to open or close it, thereby reducing the necessary mechanism for the operation of the valve. 30

Another object of the invention is to provide an operating mechanism which will have no lost motion, but which will store in 35 the spring the necessary energy for the operation of the valve, whether to close it or to fully open it.

Another object of the invention is to provide means for locking the valve open or 40 locking it shut during the movement of the mechanism and up to the moment of release, so as to prevent the inadvertent operation of the valve during the time the operating mechanism is being set for the valve 45 movement.

Another object of the invention is to provide a valve operating mechanism which will be so designed that the normal position or raising of the mechanism is with 50 the valve closed, thereby preventing danger from over-heating the boiler or preventing danger from explosion should anything go wrong with the operating means.

Another object of the invention is to 55 provide a valve operating mechanism which

will be easily adjusted to vary the boiler temperature and of such simple construction as to eliminate the danger of misadjustment when such adjustment becomes necessary.

Another object of the invention is to provide means whereby the valve will be fully opened or fully closed with a snap to prevent the flash back into the burner of the gas, as is likely to occur if the valve operates slowly. 60

An embodiment of the invention is shown in the drawings in which the same reference numeral is applied to the same portion throughout, but I am aware that there may be modifications thereof. 65

Figure 1 is a side elevation of the apparatus as it appears applied to a boiler.

Figure 2 is a side view of the apparatus partly in section and with the cover plate removed, the operating mechanism being 75 turned 90 degrees from the position shown in Figure 1, the valve being shown at the instant it has moved to the open position.

Figure 3 is a side elevation of the apparatus with the operating mechanism in process of moving from one position to another and just prior to the closing of the valve. 80

Figure 4 is a side elevation of the apparatus as it appears just an instant before the valve is to move to the open position. 85

Figure 5 is a side elevation of two of the operating levers.

Figure 6 is a side elevation of the valve stem.

Figure 7 is an edge view of one of the operating levers. 90

Figure 8 is an end view of the locking lever.

Figure 9 is an end view of the locking lever shown in Figure 8. 95

The numeral 1 indicates the hot water boiler below which is installed the burner 2 with the pipes 3 and 4 extending from the valve casing 5. At the top of the valve casing there is a pipe 6 which supplies the gas 100 to the burner and from this pipe a similar pipe 7 extends to the pilot burner 8 which is so placed as to maintain a flame over the burner 2. It will be understood by those skilled in the art that the burner 2 is of any 105 suitable type to supply the gas with the proper mixture of air to completely burn it but which forms no part of the present invention. On the side of the valve casing 5 there is a casing 9 with a cover 10 for enclos- 110

ing the valve operating mechanism. The casing 10 has a nut 11 with a thread nipple 12 thereon fitted to screw into a suitable fitting 13 in the boiler. This nut 12 has 5 a tube 14 of a suitable material to give a considerable movement upon expansion and within said tube there is a rod 15 of a material which has a very low rate of expansion to give the necessary movement to the 10 steel point 16 bearing upon one end of the lever 17. The lever 17 has one end bearing upon a fixed knife edge 18 and the other end is movable and bears upon the adjusting pin 20, which pin has an adjusting 15 screw 21 extended or retracted by the nut 22. The pin 21 bears upon a lever 23 which is pivotally held in a given position at one end by means of the fixed double knife edge 24. The lever 23 has an extension 25 and a 20 pin 26 which latter provides the pivot point for the lever 27. The arm 25 is provided with a pin 28 which pin engages an open slot in the end of a double bell crank locking lever 29, pivotally mounted on a screw 30, and which lever has a projecting lug 31 25 on its underside for locking the valve 32 in an open or closed position during the period of setting of the levers prior to the opening or closing of the valve. The valve stem 32 30 extends into the valve casing 5 and may be removed and examined if so desired by means of the plug 33. It is also provided with a collar 34 and with a notch 35 for its operation. At one end of the casing there 35 is a raised portion 37 in which the screw 30 extends and said raised portion also forms the body for receiving the screw 38 and screw 39, the former of which holds the lever 40 in its proper place and the latter of which 40 holds a strap 41 in a rigid position, the latter strap also having a screw 42 to assist in holding it.

The lever 40 is provided with a head 43 which extends into a notch on the strap or 45 plate 41, and head 44 which extends into the notch 35 on the valve stem 32, and slot 45 through which the pin 38 extends and the lug 46 which locks the valve open or closed through the aid of the lug 31 on the lever 50 29. It will also be seen that one end of the lever 27 extends into the notch 35 and bears against both sides of the same. The lever 27 has two projecting knife edges on its side as indicated at 46' and 47, and said 55 knife edges bear upon a lever 48, which lever is also provided with a knife edge at 49 bearing upon one side of the lever 23. The lever 48 is also provided with an ear 50 through which a rod 51 passes. This rod extends 60 into a boss 52 on the inside of the casing 9 and is movable longitudinally with respect thereto. The rod 51 also extends through the side of the casing 9 and is provided with a stiff spiral spring 53, the pressure of which 65 spring is adjusted by means of the nut 54.

A collar 51' on the rod 51 bears upon the ear 50 and transfers the pressure of the spring 53 to the lever 48 for the operation of the valve 32'.

In tracing out the operation of the apparatus it will be seen that the thermostatic tube 14, which is made of a metal having a high coefficient of expansion, holds the rod 15 having a low coefficient of expansion, in a position depending upon the temperature of the water in the boiler. As the temperature rises the tube 14 expands and the rod 15 moves down, see Fig. 2. As the temperature falls the tube 14 will contract in length and the rod 15 will rise. When the rod 15 moves down, on account of the lengthening of the tube 14 upon the heating of the water in the boiler, the lever 17 will move down at its right hand end, as shown in Fig. 2.

The adjustable post 20 will then permit the lever 23 to move down at the left hand end of Fig. 2 on 24 as the fulcrum. At the same time the spring 53 and rod 51 will hold the lever 48 with its knife edge 49 in contact with the lever 23 and the lever 48 will also be in contact with the knife edge 46'. At this time the knife edge 47 can separate from the lever 48 until the movement of the arm 25 has shifted the lever 29 so that the lug 46 can pass the lug 31 at its right. Thereupon the pressure of the spring 53 on the levers 48 and 27 and their pressure upon the yoke 35 will cause the valve stem 32 to move downwardly, the lug 46 passing to the right of the lug 31 as it is just about ready to do in Fig. 3. This movement will push the lever 44 downwardly so that its lug 46 will be locked below the lug 31, as appears in Fig. 4.

The valve will then be closed. As the boiler cools off the tube 14 will contract more rapidly than the rod 15 which raise the levers 17 and 23, Figure 2. This will cause the lever 29 to swing to the right (Figure 2) because it is connected with the lever 25 by the pin 28. But as such a movement raises the left hand end of the lever 48 the right hand end will be depressed and the lever 27 will tend to continue to hold the yoke 35 up and the valve 32' open, there being no tendency to close the valve till the temperature of the boiler is high enough to lower the lever 17.

From the above it will be seen that as the boiler becomes hot enough the gas valve will close while as it cools the valve will jump fully open, and in either position the lugs 46, 31 lock it against movement.

What I claim is as follows, but various modifications may be made in the construction shown in the drawings and above particularly described form, within the purview of my invention:

1. A thermostatic fuel regulator comprising

ing a fuel supply pipe, a valve therein, levers to operate the valve, a thermostatic element bearing upon one of the levers, a single spring producing a continuous pressure on the levers for causing the valve to be seated or unseated upon movements of the levers and a locking lever contacting with one of the levers for preventing the movement of the valve in either the seated or unseated position until the proper time for action thereof.

2. A thermostatic fuel regulator comprising a fuel supply pipe, a valve therein, levers to operate the valve, a thermostatic element bearing upon one of the levers, a single spring producing a continuous pressure on the levers for causing the valve to be seated or unseated upon movements of the levers, one of said levers bearing upon another of said levers, at two points and means contacting with one of the levers to lock the valve in an opened or closed position during the movement of the levers preparatory to opening or closing the valve.

25 3. A thermostatic burner regulator comprising a valve casing, a valve therein, a stem connected with the valve, a lever pivoted to the casing and having means thereon for the operation of the valve, a lever contacting with one of the levers for locking the valve in the opened or closed position during the preparatory movement of the operating levers, a rod bearing upon one of the levers, a spring carried by the rod for shifting the valve to either the closed or the open position upon suitable movement of the levers and a thermostatic element bearing upon one of the levers for operation of the apparatus.

40 4. A thermostatic fuel regulator comprising a fuel supply pipe, a valve therein, operating levers connected with the valve, a thermostatic element bearing upon one of said levers, a locking lever operated by the valve stem and contacting with one of the levers and a second lever operated by the first lever for locking the valve through the lever connected therewith in either the open or the closed position during preliminary movements of the operating levers.

5. A thermostatic regulator for burners comprising a fuel supply pipe, a casing connected therewith, a valve therein, levers connected with the valve and the casing for the operation of the valve, a thermostatic element bearing upon one of said levers, a spring the pressure of which is taken up by one of said levers, means whereby energy may be stored in said spring for the opening or for the closing of the valve and means to lock the valve open or closed during preliminary movements of the operating levers.

6. A thermostatic regulator for burners comprising a fuel supply pipe, a casing con-

nected therewith, a valve in the casing, a series of levers in the casing for the operation of the valve, a thermostatic element bearing upon one of said levers, a single operating spring for opening and for closing the valve, a lever connected with the valve and operated thereby and a second lever adapted to lock the lever just mentioned with the valve in the fully opened or fully closed position during preliminary movements of the operating levers.

7. A thermostatic regulator for burners comprising a fuel supply pipe, a casing connected therewith, a valve therein, a pair of levers pivotally mounted on the casing, a thermostatic element bearing upon one of said levers, a third lever pivotally mounted on one of the first mentioned levers and connected with the valve for the operation thereof, means to lock the valve in an opened or closed position and a single spring the pressure of which bears upon one of the levers for effecting the movement of the valve.

8. A thermostatic regulator for burners comprising a fuel supply pipe, a casing connected therewith, a valve therein, a pair of levers pivotally mounted on the casing, another pair of levers bearing upon each other and one of which is pivotally mounted on one of the first mentioned levers and connected with the valve, means to lock the valve in an opened or closed position during the preliminary movements of the levers, a single spring for effecting the changes in position of the valve and a thermostatic element bearing upon one of the levers for their operation.

9. A thermostatic regulator for burners comprising an enclosing casing, levers therein, a thermostatic element carried by the casing and bearing on one of the levers to move it, a fuel valve, a lever for positively moving said fuel valve in two directions, pivoted on one of the levers, and other levers to lock the valve open or closed as the case may be until the full action of the valve can take place.

10. A thermostatic regulator for burners comprising a support, levers carried thereby, a thermostatic element carried by the support and bearing on one of the levers to move it, a fuel valve, a lever for positively moving said fuel valve in two directions pivoted on one of the foregoing levers, other levers to lock the valve in the open or closed position and a single spring exerting pressure upon the levers to move the valve in both directions.

11. A thermostatic regulator for burners comprising a support, levers carried thereby, a thermostatic element carried by the support bearing on one of the levers to move it, a fuel valve, a lever for positively mov-

ing said fuel valve in two directions pivoted on one of the foregoing levers, means to lock the valve in the open or closed position as the case may be until the full action of the valve can occur and a spring exerting pressure upon certain of the levers for moving the valve in both directions, one of said

levers having pressure exerted thereon, first on one side and then on the other side of its pivot point.

In testimony whereof I have hereunto set my hand this 5th day of July, A. D. 1919.

WILLIAM ELMER STUART
